UNITED STATES PATENT OFFICE.

GEORGE HOWLETT DAVIS, OF WEST ORANGE, NEW JERSEY.

STAIRWAY-ELEVATOR.

1,358,062.

Specification of Letters Patent.

Patented Nov. 9, 1920.

Application filed March 29, 1918. Serial No. 225,453.

To all whom it may concern:

Be it known that I, GEORGE HOWLETT DAVIS, a citizen of the United States, residing at West Orange, in the county of Essex 5 and State of New Jersey, have invented certain new and useful Improvements in Stairway-Elevators, of which the following is a specification.

My present invention relates to elevators, 10 pertaining more particularly to structures capable of being installed in stairways, etc.

It is the general practice where conditions require the shifting of commodities from one floor to another, to install elevator mechanisms movable vertically, special provision being made for installation. For instance, elevator shafts or wells are employed, generally with some form of protective device. Where installation is made in a building 15 previously constructed, remodeling of the interior is necessarily required. In addition, the floor space occupied by the shaft or well is unavailable for other purposes. Obviously, stairways must be and are provided, 20 regardless of the presence or absence of elevators. And where both stairways and elevators are present the floor space is decreased accordingly. This decrease is especially present where elevator installation is made 25 in buildings previously built with no idea of installing elevator service.

The present invention is designed to meet these conditions by utilizing the space occupied by the stairway, causing the elevator 30 platform to travel through this space over the stairs, thus eliminating the necessity of extensive remodeling, or any material loss of available floor space.

This result is obtained by utilizing the 35 lower landing of the stairway as an elevator platform, the platform normally serving as the landing, but being movable to and from the next floor as a carrier, the movements being readily controlled. As a result, the 40 stairway is available for use at all times while the platform is in its lower position, or from above while the platform is traveling toward its lower position. Hence, the invention may be considered as a combined 45 stairway and elevator structure.

Other objects are to provide an arrangement which is simple and efficient in operation, durable in construction, and which can be manufactured and maintained at a relatively low cost and installed at a minimum 50 of cost, labor, and remodeling.

To these and other ends, the nature of which will be readily understood as the invention is hereinafter disclosed, said invention consists in the improved construction 60 and combination of parts, hereinafter fully described, illustrated in the accompanying drawings, and more particularly pointed out in the appended claims.

In the accompanying drawings, in which 65 similar reference characters indicate similar parts in each of the views,

Figure 1 is a perspective view showing one form in which my invention may be utilized.

Fig. 2 is a side elevation of parts shown in 70 Fig. 1.

Fig. 3 is a plan view of portions of the operating mechanism.

Fig. 4 is a detail elevation showing control mechanism.

Fig. 5 is a detail view, partly in section, 75 of a retaining mechanism.

Fig. 6 is a detail plan view of a reversing switch.

Fig. 7 is a diagrammatic view showing a 80 simple arrangement of control circuits.

In the drawings I have shown the invention as applied to an open stairway leading from a lower to an upper floor, the stairs being indicated at a , a hand-railing being 85 shown at a^1 , and the upper landing at a^2 . This arrangement is a common one employed in manufacturing plants occupying two floors. Where the stairway is inclosed, a wall takes the place of railing a^1 .

The sides of the stairs are formed with rails or run-ways 10, inclined to the vertical. These run-ways are formed in suitable manner, as by the edges of boards or planks, and extend below the lower step a sufficient distance to permit movements of the platform truck, as presently described. Where the installation extends from the ground floor, (the arrangements shown in the drawing), a well 11 will be provided, the rails continuing into the well. Where the installation is from an upper floor, the run-ways or rails 10 may simply extend below the floor level, extending into the room space of the floor below.

Mounted on rails 10 is a truck formed of a frame 12 having its sides preferably of a generally triangular contour this frame carrying two pairs of flanged wheels 13, the pairs being spaced apart. The frame carries a horizontal platform 14, which forms the lower landing when in lower position,

the frame, in this position, extending into the well as in Fig. 1. Since the platform is mounted on the inclined support, it will be maintained in normal position against further lowering movements by contact with a wall of the well. Hence the platform surface can be maintained flush with the floor surface while in its lower position.

The platform is moved on the rails by suitable mechanism, one form of which is shown in the drawings, where 15 indicates a pair of flexible members—shown in the form of sprocket chains connected to the platform at their lower ends by suitable members 16. The chains 15 are carried over sprocket wheels 17 at the top of the flight of stairs, the free ends of the chains having suitable counter-weights 18 adapted to balance the weight of the platform and its truck. The counterweights may be located in suitable wells 19, the chains passing over suitable idlers 20 over the wells.

Sprocket wheels 17 are mounted on shaft 21 suitably supported, said shaft being adapted to be driven by a suitable motor, electric or otherwise, preferably through a worm drive mechanism, such for instance as shown, in which 22 indicates a worm carried by the motor shaft and 23 a worm gear co-operating therewith, the shaft of gear 23 carrying a pinion 24 meshing with a gear 25 mounted on shaft 21.

By the use of the worm drive connection I am able to use a high speed motor, with the ability to employ simple control mechanism. Such connection also is of advantage through the fact that chain-movements, in either direction, are had only by motor movements, the worm and gear connection forming a lock against coasting, etc. of the platform.

As will be seen, idlers 20 are positioned materially in advance of a vertical plane extending through shaft 21, the result being that the chains are given the formation of a bight, with the sprocket wheels 17 located therein, thereby providing against withdrawal of chain links from the sprocket teeth during operation, thus reducing liability of slippage during movements of the platform. The arrangement provides the safety and power factor of an endless chain structure without requiring the chain length necessary to produce the endless chain structure, while at the same time it permits of the balancing action of the weights, enabling the use of power mechanism of lower power value with the resultant decrease in cost of apparatus and of operation.

I prefer to employ an electric motor 26 as the prime mover. This permits of the use of simple mechanism for controlling the motor operations. This mechanism may be of suitable type, Fig. 7 indicating the wiring of a simple and inexpensive reversing

switch of a well known type. In this view 27 indicates a pivoted member carrying four blades connected in pairs, these blades being adapted to contact with either of two sets of contacts 28, these contacts being connected to the motor and the source of current supply (indicated as a battery for illustrative purposes), with the connections so arranged that positioning of member 27 in engagement with one set of contacts causes motor operation in one direction, and when positioned in engagement with the other set motor operation will be in the opposite direction.

Fig. 6 indicates one form of arranging member 27 and contacts 28, member 27 being pivoted to ears 29 carried by an insulating support 30, wings of the support carrying the contacts 28. The movements of member 27 are on a vertical axis, and are provided by a connection 31 carried by pivoted levers 32, located at the bottom and top of the stairs, the arrangement connecting the two levers to move in unison with each other and with member 27.

One of the members 16 or its chain carries a bracket 33 carrying adjustable members 34—shown as threaded pins.

One of the levers 32 is pivoted to a segmental bracket 35, the lever carrying a device 36 adapted to yieldingly engage anyone of a series of notches or depressions in bracket 35. This arrangement practically locks the lever structure in either of a plurality of positions.

The normal position of the lever structure is with member 27 out of engagement with either set of contacts (Fig. 6). In this position, the platform is at rest in its lower or upper position, with device 36 engaging an intermediate notch. Bracket 33 has its members 34 operating between the levers, co-operating therewith to throw the switch.

Assuming the platform to be in its lower or normal position, the load is run on to the platform and the lower lever drawn forward or outward; inward movement is practically prevented by the presence of member 34 in the path of movement of the lever. This movement of the lever structure shifts member 27 in a direction to bring its blades into engagement with that set of contacts adapted to provide motor operation in a direction to cause the platform to be drawn upward, the chain carrying bracket 33 with it in its travel. This movement continues until the other member 34 contacts with the upper lever—shifted from normal position by the movement of the lower lever—whereupon continued movement carries the lever structure in the same direction and breaks the motor circuit by disengagement of member 27 from contact engagement, thus stopping platform movement. This brings the

platform flush with the upper floor surface, the proper timing being made possible by adjustment of members 34; at the same time the lever structure is placed in its intermediate position.

The load is removed after which the upper lever is moved outwardly—away from member 34—bringing member 27 into engagement with the other set of contacts, reversing the connections and causing the platform to travel downward. When member 34 contacts with the lower lever, movement to break the circuit is had, leaving the platform in its lower position.

Obviously, the platform may be moved from its upper or lower position by an operator at the opposite landing by simply swinging the adjacent lever inward, placing the parts in proper relation to move the platform in the proper direction.

Devices 36 will retain the lever structure in either of the positions in which it may come to rest during the manipulation while, however, permitting the structure to be readily moved by the operator.

As will be readily seen and understood, the structure is simple and efficient in operation, capable of being installed and employed under various conditions of service, and particularly adapted to meet the problems of elevator installation in previously constructed buildings without extensive remodeling and without loss of valuable floor space.

While movement from its normal position causes the platform to tend to obstruct the stairs, the ability to automatically stop platform movements and the ability to control motor movements permits the operator at the receiving landing to operate the lever immediately after unloading, thus moving the platform to its normal unobstructing position.

Obviously, movements of member 27 may be provided by connection 31, thus enabling the platform to be stopped by manual manipulation to break the circuit. This leaves the platform stationary and held against movement by the locking action of the worm drive mechanism. Advantage may be taken of this to include two or more floors in the range of platform travel, or a separate landing floor may be provided in the form of an overhead room, etc.

By adjusting members 34 proper timing in the breaking of circuits may be provided. As will be understood these members practically form stops against inward movement of the lever when the platform is at either landing position, it being obvious that when the platform is in its lower position inward movement of the lever would require movement of the chains against the weight of the platform and its load; when the platform is in its upper position inward move-

ment of the lever would require movement of the chain against the action of the worm drive connections. Hence, the particular arrangement is such that both levers are movable in opposite directions from an intermediate neutral position, but the direction of movement of the lever structure is controlled by the position of the platform.

While I have shown and described a preferred way to carry out the principles of the invention, it is obvious that changes or modifications therein may be required or found desirable to meet various exigencies of use, and I desire to be understood as reserving the right to make any and all such changes or modifications as may be found necessary, in so far as the same may fall within the spirit and scope of the invention as expressed in the accompanying claims.

What I claim as new is:

1. The combination with an inclined runway and a truck traveling thereon of power mechanism for moving the truck including chain members connected with such truck, a motor, and drive connections between the motor and chain members; means for controlling said power mechanism, said means including a reversing switch in electric circuit with the motor, levers at the ends of the runway connected to operate in unison and adapted to be shifted to start the motor in a predetermined direction; and means carried by the chain members adapted to actuate the levers at predetermined times to move the same to neutral position thereby stopping the motor and halting the truck.

2. The combination with a stairway having a well at its lower end from which extend oppositely disposed rails adapted to form a run-way substantially parallel to the general direction of the stairway, a wheeled truck adapted to run thereon so constructed that its upper face or platform normally constitutes the lower landing of the stairway when its body rests in the well, of power mechanism operative at the upper end of the stairway to move the truck, said mechanism including a driven shaft having wheels, flexible lines secured at one end to the truck and counter-weighted at their opposite ends with an intermediate portion of the lines forming a bight about said wheels to prevent slippage between the wheels and lines and control means traveling with the truck for rendering the power mechanism active or inactive so as to automatically position the platform at a predetermined level.

3. The combination with a stairway having a well at its lower end from which extend oppositely disposed rails adapted to form a run-way substantially parallel to the general direction of the stairway, a wheeled truck adapted to run thereon so constructed that its upper face or platform

normally constitutes the lower landing of the stairway when its body rests in the well, of power mechanism operative at the upper end of the stairway to move the truck, said mechanism including a driven shaft having wheels, a worm drive connection effective on said shaft, flexible lines secured at one end of the truck and counter-weighted at their opposite ends, with an intermediate portion of the lines forming a bight about said wheels to prevent slippage between the wheels and lines and control means traveling with the truck for rendering the power mechanism active or inactive so as to automatically position the platform at a predetermined level.

4. The combination with a stairway having a well at its lower end from which extend oppositely disposed rails adapted to form a runway substantially parallel to the general direction of the stairway, a wheeled truck adapted to run thereon so constructed that its upper face or platform normally constitutes the lower landing of the stairway when its body rests in the well, of power mechanism operative at the upper end of the stairway to move the truck, said mechanism including a driven shaft having wheels, flexible lines secured to the truck and leading over said wheels whereby mechanism operation will provide platform movements on the run-way and control means for the power mechanism, said means including a pivoted lever structure movable from a normally inactive position, and means movable concurrently with the platform for returning the structure to normal position when the platform has moved to a predetermined position.

40 5. The combination with a stairway having rails at opposite sides thereof adapted to form a run-way and a wheeled truck adapted to run thereon, of power mechanism for moving the truck including flexible members connected with the truck, a motor, a worm and a worm gear co-operating in driven relation therewith and gearing interposed between the worm gear and the flexible members, means including a reversing switch in electric circuit with the motor to control the movement of the truck, spaced levers so connected with the flexible members as to operate in unison and adapted to be shifted to operate the switch and start the motor in a predetermined direction and means traveling with the truck for shifting said levers to neutral position to stop the motor and hold the truck.

60 6. The combination with a stairway having a well at its lower end from which extend oppositely disposed rails adapted to form a run-way substantially parallel to the general direction of the stairway, a wheeled truck adapted to run thereon so constructed that its upper face or platform

normally constitutes the lower landing of the stairway when its body rests in the well, of power mechanism operative at the upper end of the stairway to move the truck, said mechanism including a driven shaft having wheels, flexible lines secured at one end to the truck and counter-weighted at their opposite ends, with an intermediate portion of the lines forming a bight about said wheels to prevent slippage between said wheels and the lines and control means for the power mechanism, said means including a lever structure movable from a normally inactive position at will and having pivoted members at the opposite ends of the stairway and a member entering into the power mechanism control, said members being movable in unison, and a device movable concurrently with the platform and having elements co-operative with the pivoted members for returning the lever structure to normal position when the platform has reached a predetermined position, said elements being adjustable to permit variations in the location of such latter position.

7. In combination, a stairway having a well at its lower end, a run-way extending substantially parallel to the general direction of the stairway and extending into said well, a platform mounted on and movable in directions of length of the run-way, said platform being normally seated to close said well and form a landing at the lower end of the stairway, power mechanism operative at the upper end of the stairway and including a shaft having wheels, lines secured to the platform and leading over said wheels, whereby mechanism operation will provide platform movements on the run-way over the stairs, and control means for the power mechanism, said means including a lever structure movable from a normally inactive position at will and having pivoted members at the opposite ends of the stairway, said members being connected to move in unison, and a device carried by a line and movable concurrently with the platform, said device co-operating with said lever structure to cause lever movements to return said members to normal position when the platform has reached a predetermined position.

8. In combination, a stairway having a well at its lower end, a run-way extending substantially parallel to the general direction of the stairway and extending into said well, a platform mounted on and movable in directions of length of the run-way, said platform being normally seated to close said well and form a landing at the lower end of the stairway, power mechanism operative at the upper end of the stairway and including a shaft having wheels, lines secured to the platform and leading over said wheels, whereby mechanism operation will provide

platform movements on the run-way over the stairs, and control means for the power mechanism, said means including a lever structure movable from a normally inactive position at will and having pivoted members at the opposite ends of the stairway and a member entering into the power mechanism control, said members being movable in unison; and a device movable concurrently with the platform and having elements co-

operative with the pivoted members for returning the lever structure to normal position when the platform has reached a predetermined position.

In testimony whereof I affix my signature in the presence of two witnesses.

GEORGE HOWLETT DAVIS.
